PROTECTIVE VISOR FOR INDUSTRIAL HATS

Charles William McClung, El Dorado, and Paul Ransom, Shingle Springs, Calif.

Application April 4, 1938, Serial No. 199,914

5 Claims.

(Cl. 2—10)

This invention relates generally to eye protective equipment for industrial workers and in particular the invention is directed to a protective visor for use in combination with industrial hats and especially those having hard crowns and rims and known to the trade as "hard hats."

Heretofore, industrial workers, in certain occupations such as mining where flying particles endanger the eyes, have used the common type goggle which engages the face and is uncomfortable when worn over any substantial period of time. In fact, many workers rather than wear goggles abandon the same and risk injury.

It is therefore our principal object to provide a protective visor, for use in combination with industrial hats, which is so constructed that it does not engage the face of the wearer, provides full vision, and may be easily adjusted from a position before a person's eyes to a retracted position clear of such person's line of vision.

An additional object of our invention is to provide a novel arrangement whereby the visor, when used with an industrial hat of the hard crown type, is effectively held in a retracted position.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views:

Figure 1 is a sectional elevation of the visor mounted on a hat and in a retracted position.

Figure 2 is a similar view but with the visor lowered for use.

Figure 3 is a perspective view of the visor unit, detached.

Referring now more particularly to the characters of reference on the drawing, we prefer to incorporate our protective visor (hereinafter described in detail) in an industrial hard hat including, as is usual, a crown 1, an integral brim 2, a lamp support 3 on the front of the crown, and a semi-rigid head band 4 disposed within the crown in spaced relation therefrom. The head band 4 is supported at circumferentially spaced points on the lower ends of brackets 5 by snap buttons 6; the brackets being riveted intermediate their ends to the crown 1 as at 7. The upper ends of brackets 5 are slotted and carry

the usual head engaging and shock absorbing web 8.

The visor is constructed as an integral unit and mounted in the following manner:

The numeral 9 indicates the eye shield portion 5 of the visor which is curved from side to side to conform generally to the curve of a wearer's face; this shield being cut away as at 10 to provide nose clearance. Arms 11 extend rearwardly at an upwardly slope from the sides of eye shield 9 10 adjacent the bottom thereof, said arms being curved inwardly as shown and in substantial symmetry to the curvature of the sides of head band 4.

The arms are provided with holes 12 at their 15 rear ends, and these arms are disposed between the head band 4 and brackets 5 and with the rear snap buttons 6 engaged through said holes 12. The rear ends of arms 11 are thus swingably secured between brackets 5 and head band 4. In 20 order that the arms may swing upward until the eye shield 9 is clear of the wearer's line of vision, the arms at their forward ends are cut away at the upper edge, as at 13, which permits sufficient arm movement without obstruction by the 25 forward bracket and snap button assemblies.

The shield 9 is held in retracted position (Fig. 1) by means of an integral, upwardly extending tongue or extension 14 on the eye shield 9, such extension being curved the same as the shield 30 and substantially the same as the interior surface of crown 1. Extension 14 frictionally engages the inner crown surface at all times in face to face contact and as the visor unit is somewhat resilient, the unit is held retracted until needed. To adjust the visor before the eyes, the wearer need only draw the shield downward to place; the extension then being lowered but still in close frictional engagement with the crown (Fig. 2) 35 maintaining the unit in place. This extension also, of course, provides a closure between the hat and the eye shield proper, preventing any particles from dropping between the visor and the face of the wearer.

The protective visor is made of a transparent 45 and shatterproof material and preferably that thermoplastic resin known as "Lucite" and which has fine optical characteristics.

From the foregoing description it will be readily seen that we have produced such a device 50 as substantially fulfills the objects of the invention as set forth herein.

While this specification sets forth in detail the present and preferred construction of the device, 55 still in practice such deviations from such detail

may be resorted to as do not form a departure from the spirit of the invention, as defined by the appended claims.

Having thus described our invention, what we claim as new and useful and desire to secure by Letters Patent is:

- 5 1. In the combination of a hat having a hard crown and a head band secured therein in spaced relation thereto, and a visor unit including a transparent eye shield adapted when in use to be disposed in front of the eyes of the wearer, and means mounting said eye shield on the hat for upward movement from an operative position in front of the eyes of the wearer to an inoperative position out of the line of vision of the wearer; a tongue projecting upward from said eye shield between said hat band and crown and positioned to engage the inner surface of the crown at the front of the hat in frictional holding relation.
- 10 2. In the combination of a hat having a hard crown and a head band secured therein in spaced relation thereto, and a visor unit including a transparent eye shield adapted when in use to be disposed in front of the eyes of the wearer, and means mounting said eye shield on the hat for upward movement from an operative position in front of the eyes of the wearer to an inoperative position out of the line of vision of the wearer; a tongue projecting upward from said
- 15 30 eye shield and between the hat band and crown, said tongue engaging the inner surface of the crown in frictional holding relation and being of sufficient length to so engage the crown when the eye shield is either in operative or inoperative position.
- 20 35 3. In the combination of a hat having a hard crown and a head band secured therein in spaced relation thereto, and a visor unit including a transparent eye shield adapted when in use to be disposed in front of the eyes of the wearer, side arms projecting rearwardly from the eye

shield, means pivoting said side arms at their free ends at points on the hat for swinging movement of the eye shield from an operative position in front of the eyes of a wearer to an inoperative position out of the line of vision of the wearer; a tongue projecting upward from said eye shield between said hat band and crown and engaging the inner surface of said crown in wedging relation when the eye shield is either in operative or inoperative position.

4. A visor for an industrial hat having a hard crown and a head band secured therein in spaced relation, said visor comprising a transparent eye shield curved forwardly from end to end in plan, side arms projecting rearwardly from the ends of the eye shield and being curved in concave relation to each other, means adapted to support said arms at their free ends between the crown and head band at the sides thereof, and a tongue of substantial height projecting upwardly from the upper edge of the eye shield and similarly curved, said tongue being adapted to engage the inner surface of the crown in frictional holding relation when the arms are so pivoted.

5. A device as in claim 1 in which said means comprises side arms curved in concave relation to each other and projecting rearwardly from the ends of the shield, and elements pivoting said arms at their free ends between the sides of the band and crown and for swinging movement in a vertical plane therebetween; the hat including supporting members connected and extending between the band and crown, said members intersecting the plane of movement of said arms, the upper edges of said arms being notched at a point and to a depth whereby upon upward swinging movement of said arms, the same clear said members.
